UNITED STATES PATENT OFFICE.

ERNEST L. NEUNEKER, OF NEAR BUSHNELL, ILLINOIS.

ANIMAL-TRAP.

1,244,069.

Specification of Letters Patent. Patented Oct. 23, 1917.

Application filed April 21, 1917. Serial No. 163,750.

To all whom it may concern:

Be it known that I, ERNEST L. NEUNEKER, a citizen of the United States, residing near Bushnell, in the county of McDonough, 5 and State of Illinois, have invented a new and useful Animal-Trap, of which the following is a specification.

My invention relates to that general class of traps which are self-actuated and self-10 setting, and in the body of which a number of caught animals may be held until it is desired to release them.

The principal end and object of the invention is to generally improve the construction and increase the efficiency and utility 15 of traps of this nature.

The invention consists, substantially, in the improvements hereinafter described.

In the accompanying drawings:

20 Figure 1 is a perspective of a preferred embodiment of my invention, the housing-lid being raised to show the tripping-mechanism;

Fig. 2, a transverse section taken substantially in the plane of the line 2—2 in Fig. 1;

Fig. 3, a front elevation, partly broken away; and

Fig. 4, a sectional detail hereinafter more fully described.

30 Coming now to a detailed description of the parts and designating the parts each by a reference numeral, 2 indicates a holder or compartment comprising a bottom 3, top 4, front 5, back 6, and ends 7, 7', all suitably 35 secured together by frame-pieces as shown.

The top is cut away as shown at 8 to form an opening or way in which the trip-wheel may operate. Said wheel consists preferably of a plurality of radially arranged 40 platforms 9 the inner edge of each of which is fixed to a shaft 10 rotatably mounted in bearings 11, 11' in the top 4. Fixed on one end of said shaft is a pin-wheel 12 which meshes with and is driven by a spur-wheel 45 13 which is connected with one end of a motor-spring 14 which actuates it.

The inner end of the spring is connected with the key-shaft 15 of the motor. 16 indicates a ratchet wheel fixed on said shaft 50 15, and 17 denotes a pawl fulcrumed on the spur-wheel. The motor is held in a motor-box 18.

In order that the trapped rats may be released I provide a door 19 hinged to the 55 bottom 3 at 20. 21 denotes a pin whereby the door may be secured to the bottom.

Fulcrumed on the normally upper face of each blade or platform 9, preferably by staples 22, is the middle arm 23 of a tripping and locking lever 24. The inner portion 23' of this lever is bent upward and then rearward to engage the free end of a blade-spring 25 the other end of which seats and is held in a slit in the same platform 9 to which the cooperating lever 24 is fulcrumed. The outer portion 26 of said lever is bent to extend down over the edge of the platform, and its terminal 27 is bent or directed toward the front of the trap, lying normally in a horizontal position and resting normally on the upper end of a detent rod 28 fixed rigidly to the upper front frame-bar 29 which is shown as cut away to permit of this arrangement. A double-ended tripping-platform 30 is suitably secured at its midlength to the arm 23 of each lever 24. 31 indicates a bait-holder secured to the platform 30.

32, 32' denote the ends of a housing, each end being cut away to provide an opening 37 through which the rodent may enter. 33 denotes a housing-top secured on said ends and to the top 3, and 34 indicates a lid hinged to the top 33. Any suitable approaches 35 may be provided.

The operation: Smelling the lure in the pan 31 the animal in seeking to reach it will enter the housing through one of the openings 37 and step onto one of the rotatable platforms 9. These however are 90 temporarily held from rotation by reason of the end 27 of the tripping-lever resting on the detent 28. As the animal approaches the bait he must step onto the adjacent elevated end of the tripping-platform and 95 thereby depress it, and as the tripping-platform is fixed to the tripping-lever it will rock it and thereby cause the lever-terminal to rock off from the detent 28. This releases the trip-wheel. The weight 100 of the animal will of course cause it to rotate, for the oppositely arranged platform 9 acts as a counterweight for the one on which the animal is standing. This rotation of the trip-wheel ordinarily is sufficiently rapid to throw the animal down into the holder 2, but in order that he may not rush out of one of the openings 37 before he is dumped into said holder I have provided the motor hereinbefore described, the 105 spring of which, through the gear-wheels and the shaft 10, will cause the trip-wheel

to move with accelerated rapidity. It will make only a one-fourth rotation, for when it has moved to that extent the next oncoming tripping-lever terminal 27 will strike 5 upon and be stopped by the detent 28.

I realize that considerable variation is possible in the details of this construction without departing from the spirit of my invention. Therefore I do not intend to 10 limit myself to the specific form shown and described except as pointed out in the following claim, in which it is my intention to claim as broadly as is permitted by the state of the art all the novelty inherent in 15 the invention.

I claim as new:

In a trap, a receptacle having an opening in its top, a trip-wheel rotatably mounted

in said opening and comprising a plurality of radially arranged platforms each of 20 which is adapted to close said opening, rocking-levers fulcrumed one on each platform, tripping-platforms secured one to each lever and adapted to rock it, blade-springs secured one to each radially arranged platform and 25 standing parallel with an adjacent radially arranged platform, the end of each spring secured to the tripping-lever, and a detent secured to the receptacle, an end portion of any one of said levers adapted to strike 30 upon and be detained by the end of the detent.

In testimony whereof I hereunto set my hand this 16th day of April, 1917.

ERNEST L. NEUNEKER.
